NECKTIE RACK

Sheridan C. Waite, Buffalo, N. Y.

Application July 28, 1938, Serial No. 221,754

3 Claims. (Cl. 211—96)

This invention relates to necktie holders, and has for one of its objects the provision of a simplified and improved necktie rack that is adaptable for use in different manners to suit different 5 accommodating conditions. Another object of the invention is to provide a rack for neckties which is adapted to support a plurality of neckties thereon in an improved manner. Other objects and advantages of the invention will 10 appear from the claims and from the specification which is exemplary thereof.

In the drawing:

Fig. 1 is a fragmentary plan view of my necktie rack when mounted in a horizontal position 15 upon a wall or other supporting surface;

Fig. 2 is a side elevation of my necktie rack when mounted in a vertically disposed position upon a wall or other supporting surface;

Fig. 3 is a section, on a larger scale, taken 20 substantially along line III—III of Fig. 1, through one of the bracket members of the device;

Fig. 4 is a view partly in section and partly in elevation showing the method of connecting structural elements of the device; and

Fig. 5 is a fragmentary perspective of a structural element of the device.

My invention involves generally the provision of an arm element which is pivotally mounted at one of its ends upon a supporting structure 30 for movement of its opposite end in an arcuate path toward and away from the user, and a series of headed pin elements extending laterally from said arm for supporting a plurality of neckties when arranged in looped relation thereon. The arm element of the device may be mounted upon a wall or other supporting surface in either horizontally or vertically swingable relation for movement away from the wall to give the user ready access to the neckties thereon. When not being serviced, the arm may be swung inwardly toward the wall to provide a novel locking action for maintaining the neckties thereon against accidental displacement. Certain advantageous details of construction 45 combine to make the device particularly satisfactory in operation, as will be explained hereinafter.

Fig. 1 illustrates in plan view my necktie rack when mounted in horizontally swingable relation upon a vertical wall surface 10. The rack comprises an arm member 12 in the form of a bar of wood, metal, or any other suitable substance; and it is provided at one of its ends (Fig. 5) with a vertically disposed opening 14 to receive therein a pin 16 for pivotally mounting the

arm 12 upon a bracket 18 which is adapted to be secured against the wall, as by means of screws 20, or any other suitable fastening means. The arm 12 is formed with a series of openings 22 extending therethrough in transverse relation relative to the opening 14, for receiving reduced end portions 24 (Fig. 4) of opposed necktie carrying pins 26. The pins 26 may be of rounded or any other sectional form as may be desired, and are provided with enlarged head portions 28 at their outer ends for maintaining the neckties against sliding sideways therefrom. The junctures between the pins 26 and the arm 12 may be of friction fit or glued or any other desired form.

A second bracket 30 (Figs. 1 and 3) is provided with an arm receiving opening 32 extending inwardly from a front face portion thereof for sliding reception of the outer swinging end portion of the arm 12. The bracket 30 is provided with openings 34 for the reception of screws or the like for securing thereof upon a portion of the wall or other supporting surface opposite the bracket 18 and in such manner that when the arm 12 is swung inwardly toward the wall the opening 32 registers with and receives the extending end portion of the arm 12 in free slide fitting relation. The bracket 30 is counterbored as at 36 through the opening 32 to provide a friction fitting opening for the inner end portion of a pin 38 which is attached to the arm 12 as by being disposed within an opening 40 therethrough. The pin 38 is preferably provided with an enlarged head 42 to form a convenient finger piece for the user when swinging the arm 12 toward and away from supported relation with respect to the bracket 30.

The necktie carrying pins 26 are adapted to receive neckties in draped relation thereon in such manner as to be conveniently displayed and secured against accidental displacement therefrom by means of the heads 28. When the arm 12 is positioned against the wall 10 as shown in Fig. 1, the inner group of pins 26 are adjacent the wall and an added precaution against accidental displacement of neckties therefrom is automatically provided. It is therefore impossible for the neckties to slide off the pins between the wall and the heads 28 when the arm 12 is in its "against the wall" position. The friction fit of the pin 38 and the opening 36 of the bracket 30 normally maintains the arm 12 in its "against the wall" position, but the headed end portion of the pin 38 provides convenient means for the grasp of the user when drawing

the arm 12 outwardly away from the wall toward himself whenever he wishes to take a necktie therefrom or to replace it.

This necktie rack is also adaptable for installation in horizontally restricted places, such as between pieces of furniture and adjacent room wall portions, which would not conveniently accommodate installation of the rack in the horizontally swingable mounting arrangement hereinabove described. As illustrated in Fig. 2, the bracket 18 may be mounted horizontally upon the wall surface 10, and the arm 12 pivotally mounted thereon at its end adjacent the opening 40, as by means of the pin 16 being inserted through the opening 40 and the registering pin receiving openings of the bracket 18. Thus, the arm 12 is arranged to be suspended from the bracket 18 in downwardly extending relation and swingable in a vertical plane normal to the wall 10 and outwardly therefrom about the pin 16 as a center. Under this condition of installation the necktie carrying pins 26 extend in parallel relation with respect to the wall surface 10 and are adapted 25 to support neckties thereon in overlapping relation with respect to one another. Thus the neckties lock one another in position upon the rack against accidental displacement therefrom. In connection with this type of installation the 30 finger pin 38 may be inserted in the opening 14 of the arm 12 to extend laterally therefrom toward the user to provide a conveniently disposed finger grip element.

It will be apparent that the bracket 18 may 35 also be mounted in suspended relation from the underneath surface of a horizontally extending supporting element, such as a shelf or the like, and may thus also support the arm 12 for vertically pivotable movement of the type provided for 40 by the mounting arrangement of Fig. 2. Also, it will be understood that the arm 12 may be mounted upon the bracket 18 of Fig. 1 by means of a pin connection through the opening 40 instead of through the opening 14. In such case 45 the pins 26 will be disposed vertically, above and below the arm 12, and the upper row of pins will serve to space and maintain neckties draped over the arm 12 against longitudinal movement relative to the arm.

50 Thus, a necktie rack device has been provided which is adaptable for use in a variety of accommodating conditions and which is capable of effectively supporting neckties thereon in an improved manner under different conditions.

55 Although only one form of the invention has been shown and described in detail, it is apparent to those skilled in the art that the invention is not so limited but that various changes may be made therein without departing from the spirit

of the invention or from the scope of the appended claims.

I claim:

1. In a necktie rack, an elongate arm carrying a plurality of necktie supporting fingers extending laterally therefrom, a bracket adapted to be mounted upon a wall or other supporting surface in extending relation therefrom and to support said arm at one of its ends thereon in pivotable relation, and a second bracket adapted to be mounted upon said wall or other supporting surface and having a recess therein adapted to receive the other of the ends of said arm in free sliding relation therein, a pin mounted upon and extending through said arm and having an end portion disposed in registry with said recess and an oppositely disposed headed end portion to provide a convenient finger gripping portion, said second mentioned bracket being formed with a second recess in registry with said inwardly extending end portion of said pin and adapted to receive said pin end portion in friction fitting relation.

2. A necktie rack comprising an elongate arm member carrying a plurality of laterally extending necktie holding finger elements thereon and being provided with an elongate opening therethrough adjacent one of its ends and a second elongate opening therethrough adjacent the other of its ends, said first and second mentioned openings having their major axes disposed in intersecting planes, and a bracket for mounting upon a supporting surface and including a pin element adapted to be selectively inserted into either of said openings whereby said arm may be pivotally mounted at either of its ends upon said bracket for swinging movement relative to said bracket support with said finger elements being disposed either parallel or normal to said bracket supporting surface.

3. A device for supporting a plurality of neckties comprising a bracket adapted to be mounted upon a supporting surface and including an extending pivot pin element, an elongate arm provided with a series of openings therethrough adapted to accommodate necktie supporting pins, one of said openings at one end of said arm being also adapted to receive said pivot pin for pivotal connection of said arm to said bracket, the others of said openings being parallel to one another and disposed in a plane intersecting the plane of said one of said openings, one of the others of said openings being located at the opposite end of said arm and being also adapted to receive said pivot pin for pivotal connection of said arm to said bracket in an alternative form of mounting relation.
